ASH RECEPTACLE

John Visser, Grand Rapids, Mich., assignor, by
mesne assignments, to Reconstruction Finance
Corporation, Detroit, Mich., a corporation of
the United States

Application July 1, 1939, Serial No. 282,431

3 Claims. (Cl. 206—19.5)

This invention relates to ash receptacles, and more particularly to ash receptacles for use in vehicles and adapted to be mounted in an upright panel or other member in the vehicle.

An object of this invention is to provide an ash receptacle whose housing can be made with a slight taper or draft so that it may be produced by die-casting and be made integral with a die-cast panel, door or similar member.

Another object of this invention is to provide an improved simplified ash receptacle insertable bodily and endwise in a suitable support and readily removable from the support for cleaning, as well as for emptying the contents of the receptacle.

A further object of this invention is to provide an ash receptacle of the drawer type which slides in its support on a single narrow guide and operates with the minimum of friction.

In accordance with the general features of this invention, there is provided an ash receptacle for a vehicle or the like comprising a drawer-like container insertable endwise into a suitable pocket, the pocket, if desired, being formed integrally with a die-cast panel or other member, and the ash receptacle and pocket being provided with a cooperating rib and groove for guiding the receptacle into the pocket.

Other objects and features of this invention will more fully appear from the following detailed description taken in conjunction with the accompanying drawings which illustrate one of the preferred embodiments thereof, and in which:

Figure 1 is a longitudinal vertical section through the ash receptacle of this invention, showing the ash receptacle in closed position;

Figure 2 is a view similar to Figure 1, but showing the ash receptacle in open position;

Figure 3 is a plan view of the ash receptacle proper as it appears when withdrawn from its retainer;

Figure 4 is a face view of the ash receptacle in its retainer;

Figure 5 is a plan view of the retainer without the ash receptacle;

Figure 6 is a cross section on the line VI—VI of Figure 1, looking in the direction of the arrows;

Figure 7 is a cross section on the line VII—VII of Figure 1, looking in the direction of the arrows;

Figure 8 is a fragment of a cross section similar to Figure 6, illustrating a modification of a portion of the device.

As shown on the drawings:

The particular embodiment of the invention shown in the drawings is mounted in a retainer 10 which is formed integrally with a die-cast panel member 11. The panel member 11 may be a portion of the instrument panel, the door of a storage compartment, an escutcheon plate or the like, depending upon where it is desired to mount the ash receiver. The retainer 10 is substantially cylindrical in shape, being made with a small amount of draft or taper to facilitate its production by the die-casting process. It extends back from an opening in the panel member 11 and is provided with a rear wall 13 so as to form a socket or pocket in the panel 11 for receiving the ash receptacle 14.

The bottom of the retainer 10 is formed with a longitudinally extending rib 15 on the inside, and the ash receptacle 14 is formed with a longitudinally extending groove 16 adapted to receive the rib 15, the rib 15 and groove 16 being slidable with respect to each other and forming guide means for the receptacle 14 in its movement into and out of the retainer 10.

As may be seen from Figures 6 and 7, the ash receptacle 14 has approximately the same shape as the retainer 10 in which it fits, but is somewhat smaller so that a small clearance is left all around the ash receptacle 14 except where the groove 16 in the bottom of the ash receptacle fits down upon the rib 15 of the retainer. In order to keep the ash receptacle 14 from rocking to either side upon the rib 15, a pair of spring pressed rollers 17 are provided to bear down

upon the upper edges 18 of each side of the ash receptacle. The lateral spacing of the rollers 17 prevents the receptacle 14 from rocking and coming into contact with the sides of the retainer, so that the only frictional contact between the receptacle 14 and the retainer 10 as the receptacle is moved in and out is along the rib 15 and groove 16. The entire pressure from the rollers 17 is transmitted to the relatively narrow engaging surfaces of the rib 15 and groove 16, so that the pressure between these two surfaces is great enough per square inch to cause them to become polished by their sliding upon each other and to operate with very little friction.

The rollers 17 are carried upon the inwardly bent ends of a U-shaped wire spring 19 secured to the top of the retainer 10 by a clip 21 riveted or screw-fastened to the retainer. The top of the retainer 10 is flat so that it does not rise entirely above the rollers 17 and is provided with

rectangular apertures 22 into which the rollers 17 project. The apertures 22 permit the rollers 17 to spring up when necessary, and the ends of the apertures 22 form shoulders facing the ends of the rollers 17 to keep them from sliding axially upon the end of the spring 19 upon which they are rotatable. The apertures 22 are provided with narrow extensions 23 through which the ends of the spring 19 extend to the rollers.

In order to prevent the ash receptacle 14 from accidentally being withdrawn too far from the retainer 10, the two upper edges 18 of the receptacle upon which the spring-pressed rollers 17 ride are formed with bosses or humps 24 which come up against the backs of the rollers 17 when the receptacle 14 is pulled out to its normal open position shown in Figure 2. The rollers 17 and the bosses 24 are placed so that, when the receptacle 14 is in its open position, the rollers 17 will be approximately in line with the centers of the portions of the rib 15 and groove 16 which are still in engagement, in order to provide the maximum amount of stability in both directions for the ash receptacle when it is open.

When it is desired to remove the ash receptacle 14 to empty it, all that is necessary is to pull it hard enough to cause the bosses 24 to pass under the rollers 17, whereupon the receptacle may be easily withdrawn completely from the retainer 10 and inverted to discharge its contents.

The ash receptacle 14 is formed of four pieces of sheet metal 25, 26, 27 and 28, a handle 29, and a fastening element 31, such as a screw, for the handle. The piece of metal forming the body 25 of the ash receptacle extends from one of the upper side edges 18 of the receptacle down and around across the bottom and up the other side to the other side edge 18, the center of the bottom being formed into the groove 16 which rides on the rib 15 in the retainer. The two edges 18 of the body 25 are flat except for the humps 24 and form the tracks upon which the rollers 17 ride. The rear edge of the body 25 is bent in to form a flange 32 against which the back plate 26 fits and to which it is spot-welded, and the front edge of the body 25 is bent out to form a flange 33 upon which the front 27 of the ash receptacle is secured.

The outer part of the ash receptacle front 27 fits flat against the front flange 33 of the ash receptacle body 25 and its edge 34 is bent around the edge of the flange 33 in order to secure the ash receptacle front 27 to the body 25. At the top, the edge of the ash receptacle front 27 is bent back to form a narrow flange whose edge bears against the face of the panel member 11 above the retainer 10 when the ash receptacle is in its closed position, and the flange 34 at the bottom of the ash receptacle front bears against the face of the panel member 11 below the retainer 10, as shown in Figure 1.

The central portion of the ash receptacle front 27 is dished in and carries the handle 29 at its center, the handle being fastened by a screw or other fastening element 31 extending into it from behind. The dishing-in of the ash receptacle front 27 is great enough so that the handle or knob 29 does not project any appreciable amount beyond the plane of the outer portion of the front. Thus, when the ash receptacle is in closed position, there is nothing projecting an appreciable distance beyond the face of the panel member 11 and no additional hazard is presented

to an occupant of the motor vehicle who may be thrown up against the panel member 11 by a sudden stop of the vehicle.

Besides securing the handle 29, the fastening element 31 extends through a lug 35 extending down from the baffle 28 and lying flat against the back of the central portion of the ash receptacle front 27. This fixes the baffle 28 which extends diagonally down from above the center of the ash receptacle front towards the lower rear corner, the baffle 28, however, terminating short of the bottom and end of the receptacle. The front portion of the baffle 28 is shaped to provide a pair of horizontal extensions 36 which fit around at each side of the rearwardly projecting central dished portion of the front 27.

It will be noted from Figure 2 that the baffle 28 projects just past the plane of the panel member 11 when the ash receptacle is in its open position. Thus, any ashes which are deposited in the receptacle slide back on the sloping baffle 28 to the back of the receptacle where they will be well out of the way of any currents of air or drafts sweeping across the front of the panel member 11 and perhaps into the receptacle itself. It will also be noted that the lower edge of the baffle 28 is spaced far enough above the bottom of the receptacle 14 to allow cigarette butts and the like to work their way forward to the front of the receptacle, instead of piling up at the back, thus permitting the full capacity of the receptacle to be utilized.

The ash receptacle may be provided with a snuffer of any conventional form. In the form shown in the drawings, the snuffer 37 is formed on the end of a tongue 38 which extends forward from and is integral with the upper edge of the back plate 26. The end of the tongue forming the snuffer 37 is formed into a shallow depression, and four segmental holes 39 are punched in this depression so as to form, in effect, a round hole having a pair of cross bars 41 extending across it. In using the snuffer, the lighted end of the cigarette to be extinguished is pressed down into the concave and apertured portion of the snuffer, and the burning particles of tobacco are forced through the holes 39 and knocked off the end of the cigarette by the cross bars 41.

A modified form of roller and roller spring is shown in Figure 8. In this form, the roller 43 is provided with a flange 44 which projects down beside the upper edge 18 of the receptacle upon which the roller 43 rides. The roller 43 is mounted on a spring 45 generally similar to the one shown in Figures 5, 6 and 7, but entering the roller from the inner end instead of the outer. Sliding of the roller 43 towards the center of the retainer is prevented by the adjacent portion of the spring 45, and sliding in the other direction is prevented by a shoulder 46 formed by the side of the aperture in the retainer in which the roller is located. This construction positively prevents tipping of the ash receptacle 14 upon its guide at the bottom of the retainer 10 and eliminates the possibility of the ash receptacle rubbing on the side of the retainer.

From the above description, it will be seen that I have provided an extremely simple ash receptacle which is easy and smooth in its operation and which is extremely inexpensive to manufacture. It will also be seen that I have provided an ash receptacle which is easily removed for the emptying of its contents and which is so constructed that the contents cannot be blown out by a draft or strong current of air.

It will also be seen that I have provided an ash receptacle which presents no hazards to the occupants of a motor vehicle in case of an accident and which has an attractive appearance.

It will, of course, be understood that numerous details of construction may be varied through a wide range without departing from the principles of this invention, and it is, therefore, not the purpose to limit the patent granted hereon otherwise than is necessitated by the scope of the 10 appended claims.

I claim as my invention:

1. In a container assembly including a supporting structure having an opening and a container movable into and out of said opening, said 15 supporting structure including a portion adapted to cover said container when said container is moved into said opening, rollers located in apertures in said cover portion and engaging the top edge of said container, and bearings mounted on said supporting structure extending through said rollers for securing said rollers to said supporting structure, the sides of said apertures forming shoulders at the ends of said rollers for preventing endwise movement thereof on said 20 bearings.

2. In a container assembly including a supporting structure having an opening and a container movable into and out of said opening, said supporting structure including a portion forming a cover for said container when said container is moved into said opening, a pair of rollers located in openings in said cover portion and bearing on the top edge of said container, and a wire spring having its central portion fixed to said supporting structure and the ends thereof extending through said rollers and forming bearings therefor, the sides of said openings providing shoulders for preventing sliding of said rollers on said wire spring.

3. An ash receptacle having a rearwardly dished sheet metal front, a handle located in the dished portion of said front, a baffle in said receptacle having portions extending forward around at the sides of said dished front, said baffle having a lug located between said forwardly extending portion and lying flat against the back of said dished front, and a fastening element extending through said lug and said dished front and into said handle for simultaneously securing said baffle and said handle.

JOHN VISSER.
